EDWIN G. BUSSE AND HERBERT W. EKHOLM, OF CHICAGO, ILLINOIS, ASSIGNEES TO
CHICAGO RAILWAY EQUIPMENT COMPANY, OF CHICAGO, ILLINOIS, A CORPORATION
OF ILLINOIS

SAFETY GUARD FOR BRAKE RODS

Application filed March 16, 1931. Serial No. 522,874.

The invention relates to railway rolling stock and consists particularly in novel means for safeguarding bottom connecting rods for brake beams.

5 Various devices have been developed for use in connection with truss type brake beams for preventing bottom connecting rods from dropping to the track in case of loss of connecting pins. These devices have, however, 55
10 been secured either to the spring plank or other convenient truck part, or to the compression member of the brake beam. Such devices are not adapted for use in connection with clasp brake arrangements, wherein 60
15 the bottom connecting rod does not pass beneath the spring plank or any of the compression members. Nor are these devices adapted to be applied to the front end of the 65
20 brake beam, especially if the tension member is round, because of the danger of the guard being struck and turned by obstacles 70
75 on the track.

The main object of the present invention is to provide an economical efficient bottom 75
25 rod safety guard which may be rigidly attached to the front end of a brake beam. This object and others are attained in the structure illustrated in the accompanying drawings in which—

30 Figure 1 is a vertical longitudinal section taken approximately on the longitudinal center line of a truck embodying one form of the invention.

Figure 5 is a detail top view of the safety 80
35 support shown in Figure 1.

Figure 6 is a detail front view of the same.

Figures 2, 3, 4 and 7 to 23 are detail views showing various modifications of the invention.

40 Figure 1 shows a portion of a truck including side-frame 1 carried upon wheels 2 through the usual journal boxes (not shown), and having a central opening for receiving the ends of a spring plank 3. A 85
45 bolster, portions of which are shown at 4, is carried on springs (not shown) resting on the spring plank.

Two truss type brake beams are provided for application to each pair of wheels, each beam including a compression member 5,

a tension member 6, and a strut or fulcrum arm 7 engaging the tension member at its forward end. Brake heads 8 are mounted on the ends of each beam and are suspended from the truck frame by suitable hangers 9. 55
50 The clasp brake rigging includes overhead rod 10 and link 11 secured to opposite ends of an equalizing lever (not shown), floating levers 12 and 13, dead levers 14 and 15, and bottom connections 19 and 20.

55
60 Figures 5 and 6 are detail top and front views, respectively, of the safety guard 16 shown in Figure 1. The guard is of round section and has one end 18 secured in a bifurcated bracket 17 depending from the front end of strut 7. The guard then extends upwardly in front of tension member 6 and over the top and then downwardly in the rear thereof (Figure 6), and passes beneath the strut and bottom connection 19 and then upwardly hooking over the tension member 6.

65
70 This form may be made applicable to either right or left hand bottom connections, as shown in Figure 23, by the provision of strut engaging portions 63 and 64 at each end of the guard 65.

75
80 In Figures 2 and 3, detail front and top views, respectively, an end of the guard 22 is secured in a bifurcated bracket 21 depending from the strut. The guard passes behind and then over the tension member 6 and then terminates in a hook beneath the bottom connection. Figure 4 is a side view 85
85 of a slightly varied form in which the guard 23 engages the brake beam as in Figures 2 and 3, but inclines forwardly of the bottom connection instead of depending substantially vertically.

90
95 In Figure 7, guard 24 hooks around strut 26 adjacent its intersection with tension member 25, passes up over the inside of the tension member, and then forms a hook beneath the bottom connection 27.

95
100 Figures 8 and 9 are front and side views, respectively, of another modified form of the invention in which one end of guard 30 is secured in a bifurcated bracket 28 projecting from the top of the front end of strut 29. The guard passes beneath the strut, then up

over the inside of the tension member 32, and then downwardly to form a hook beneath bottom connection 31.

In Figure 10, guard 33, shown in full lines, 5 is secured between the legs of bracket 34, depending from the forward end of strut 35, by means of a pin 42. The guard passes in front of and over tension member 36, and then downwardly forming a hook under the 10 bottom connection 37. This form may be varied as shown in dotted lines wherein the guard does not engage the tension member.

In Figure 11, one end of guard 38, shown in full lines, is secured in bifurcated bracket 15 39, as in Figures 5 and 6. The guard passes beneath the bracket and bottom connection 40 and then hooks over the right side of tension member 41. This form may be varied as shown in dotted lines.

20 In Figure 12, guard 43 has a hook 44 at one end which engages a suitable recess near the forward end of strut 45. The guard extends beneath the tension member 46, passes in front of and over the same, and then forms a 25 hook beneath bottom connection 47.

In Figures 13, 14, and 15, an end 49 of guard 52 is secured to forwardly projecting ears 50 on strut 51. The guard passes over the tension member 53, then downwardly beneath the strut, then up behind and over the tension member, and then down in front of the tension member to form a hook beneath the bottom connection 54.

30 In Figures 16, 17, and 18, a flat strap 55 has a U-shaped portion 56 at one end for insertion between the forwardly projecting strut ears 57. The assembly is maintained by a pin 59, and an additional member 58 is provided to prevent the loss of the pin. The 40 safety guard 55 depends downwardly from the ears 57 and forms a hook beneath rod 62. In Figure 18, portions of a fourth point support chair 60 and a brake beam guard, guide, or support member 61 are shown. This form 45 of guard could be advantageously used in connection with a solid type of brake beam in which case the guard would be secured to the front end of the fulcrum arm or a suitable bracket thereon.

50 In Figures 19 and 20, a loop 63 is secured between ears 64 on the forward end of strut 65 by means of pin 66. In this form, the guard is formed preferably of spring material so that the tendency of the guard to expand within the ears serves to prevent rattling.

55 Either of the guards shown in Figures 16 to 20, if desired, may be applied to a bracket depending from the front end of the strut. In 60 Figure 21 a flat strap 66 is inserted between the legs of a bracket 67 depending from the end of strut 68 and held by a pin 69 in a manner similar to that illustrated in Figures 16 to 18. Figure 22 corresponds with Figures 65 19 and 20 except that looped guard 70 is se-

cured to depending bracket 71 on strut 72. The engagement of the guard with the bracket legs is the same as in Figure 19.

It will be seen that in most of the forms shown, the guard engages both the strut and the tension member in a manner to provide effective support for the bottom connection in case of loss of a connecting pin, and also to resist lateral or longitudinal blows caused by striking obstacles between the rails, without tilting and without subjecting projecting brackets or ears on the strut to undue strain which might cause these parts to be broken. The guards are readily removable, but the use of resilient material permitting yielding engagement between the guard and brake beam is not essential in any of the forms, although it is desirable in the last.

Obviously, the invention might be varied in other respects as to details without departing from the spirit thereof and we contemplate the exclusive use of all such variations as come within the scope of the claims.

We claim:—

1. A safety guard for a railway brake bottom connection having a portion adapted to be applied to the front end of a brake beam fulcrum arm, and a portion shaped to extend beneath the connection to be safe guarded.

2. A safety guard for a railway brake bottom connection and having portions adapted to engage the forward end of the strut and the tension member of a truss type brake beam, respectively, and a portion adapted to extend beneath the connection to be safe guarded.

3. A safety guard for a railway brake bottom connection including a portion secured to the front end of the strut of a truss type brake beam, a portion engaging the tension member of the beam to prevent the guard from tilting, and a portion extending beneath the connection to be safe guarded.

4. A safety guard for a railway brake bottom connection including a portion shaped to extend beneath the connection to be safe guarded, a portion adapted to be looped over the tension member of a truss type brake beam, and a portion for engaging the forward end of the strut of said beam for preventing rotation of said guard around said tension member.

5. In combination, a truss type railway brake beam including a tension member and a strut, and a brake bottom connection safety guard secured to said strut at a point adjacent its intersection with said tension member.

6. In combination, a truss type railway brake beam including a tension member and a strut, said strut having a bracket projecting from the front end thereof, and a safety guard for a brake bottom connection and including a portion secured to said bracket, a

portion looped over said tension member, and a portion for extending beneath the bottom connection.

7. In combination, a truss-type railway 5 brake beam including a tension member and a strut, and a safety guard for a brake bottom connection and including a portion extending beneath the connection, a portion secured to said strut adjacent its intersection 10 with said tension member, and a portion looping over said tension member.

8. In combination, a railway brake beam including a fulcrum arm, said arm having a bracket projecting therefrom, and a safety 15 guard for a brake bottom connection comprising an elongated member having a portion engaging said bracket and a portion extending beneath the connection to be safe guarded.

20 9. In combination, a truss-type railway brake beam including a strut and a tension member, said strut having a bracket projecting therefrom, and a safety guard for a brake bottom connection comprising an elongated member having a resilient portion at one end secured to said bracket, and another portion extending beneath the bottom connection to be safe guarded, said resilient portion serving to prevent rattling.

30 10. In combination, a truss type railway brake beam including a strut and a tension member, said strut having spaced elements projecting from the front end thereof, and a safety guard for a brake bottom connection 35 comprising a strap having resilient portions inserted between said elements, a pin securing said portions to said elements, and a pin retaining member also secured between said elements and having a portion overlapping 40 one of said elements and engaging the head of said pin.

11. A brake beam bottom connection safety guard including portions at each end for engaging the front end of a brake beam strut, 45 and intermediate portions shaped to loop over the tension member of the beam and extend beneath the connection to be safeguarded, respectively, said guard being adapted to safeguard a connection offset at either side 50 of the center of said beam as determined by the one of said end portions which engages the strut.

12. In combination, a railway brake beam including a fulcrum arm having a bracket 55 on the forward end thereof, and a safety guard for a brake bottom connection comprising an elongated member having end portions disposed to selectively engage said bracket and intermediate portions shaped to 60 extend beneath the connection to be safeguarded, the one of said end portions engaged by said bracket being determined by the position of said connection relative to said bracket.

65 13. In combination, a railway brake beam

including front and rear parts spaced a substantial distance transversely thereof, and a brake bottom connection safety guard carried by said front part alone, said guard and front part including interengaging elements holding said guard against tilting relative to said beam.

70 14. In combination, a railway brake beam including front and rear parts spaced a substantial distance transversely thereof, and a 75 brake bottom connection safety guard carried by said front part alone and having elements for selectively attaching said guard to said front part in a plurality of positions as determined by the position of the connection 80 to be safeguarded.

In testimony whereof we hereunto affix our signatures this 10th day of March, 1931.

EDWIN G. BUSSE.
